HANGER FOR ARTICLES OF CLOTHING

George S. Nalle, Jr., Austin, Tex.

Application July 14, 1958, Serial No. 51,762

Term of patent 14 years

(Cl. D80—8)

Fig. 1 is a perspective view of a hanger for articles of clothing embodying my new design;

Fig. 2 is a side elevation;

Fig. 3 is an end elevation.

I claim:

The ornamental design for a hanger for articles of clothing, as shown.
